UNITED STATES PATENT OFFICE.

RICHARD W. STEWART, OF AUBURN, NEW YORK.

CLAMP.

Application filed February 15, 1924. Serial No. 693,086.

The object of this invention is the provision of a permanent retaining clamp for partly wound springs for motors of a design and construction that will eliminate the necessity of the winding in of motor springs into the spring barrels and likewise eliminate the operation of winding out of broken springs for replacement by new ones.

Another object is the construction of a permanent retaining clamp for motor springs which is adjustably secured around a partly wound spring to remain a permanent fixture therewith and which is of such construction and arrangement as to not interfere with the insertion of the spring in the spring barrel and the locking engagement of the same therewith, and which is also of a construction that the spring may be readily removed from the spring barrel.

To the attainment of the foregoing and other objects which will present themselves as the nature of the invention is better understood, reference is to be had to the drawing which accompanies and which forms part of this application.

In the drawing:—

Figure 1 is a perspective view of a partly wound spring held from expansion by a clamp in accordance with this invention.

Figure 2 is an approximately central longitudinal sectional view through a portion of the spring and the connected ends of the clamp.

Figure 3 is a sectional view substantially similar to Figure 2, but showing the spring arranged in the spring barrel and the eye or opening thereof engaging the anchor of the barrel.

Figure 4 is a fragmentary perspective view of one end of a spring which has its end centrally notched and provided with hooks at the opposite sides of the notch for engagement with an anchor or with a post in a spring barrel, the dotted lines indicating the position of the improved clamp on the spring.

Figure 5 is a perspective view of the clamp.

Figure 6 is a view of the end of a spring provided with different post receiving openings.

It is a common practice in factories for spring motor operated mechanisms, such as phonographs and the like, to wind the motor spring to an extent that will render the same of a size to be inserted in the spring barrel.

The spring is held partly wound by a wire arranged therearound and which has its ends twisted. The wire clamp is not a permanent affair, and the same must be removed when the spring is arranged in the barrel. As the description progresses, it will be seen that my improvement contemplates the employment of a permanent clamp for springs which are thus partly wound and which will slip with the spring into the barrel, permitting the outer end of the spring to be engaged by the anchor or post in the barrel and in no way interfering with the operation of the motor.

Referring now to the drawing in detail, a partly wound spring is indicated by the numeral 1. The spring has its outer end offset to provide a tongue extension 15 that is formed with a slot or opening 2 to engage the post 3 in the barrel 4. The spring 1 has arranged therearound a comparatively thin metal strap 5. The strap gradually decreases in width from one to its opposite end and its widened end is provided with spaced openings 6. The reduced end of the strap 5 is passed through the slot or opening 2 in the tongue 15 and has its extremity received in one of the openings 6 and is bent under the body of the strap proper. The thickness of the clamping strap 5 is less than the distance between the tongue end of the spring and the coil adjacent to said tongue, so that the tongue may be forced toward the spring to permit of the latter being inserted in the barrel, when a release of such pressure on the tongue will allow the same to spring outwardly and to receive the post 3 in the opening 2 in the said tongue. Of course, the spring is turned in the barrel either before or after the shaft is secured to the inner end thereof to bring the post 3 into contact with the outer end wall provided by the opening 2. I have found that by turning the barrel on its side and lightly tapping the same the spring will turn in the barrel so that the post 3 will ride out of the slot in the tongue. It is to be noted that the opening 2 extends through the inner end of the tongue 15 and enters the outer end of the spring 1. By providing the strap with a plurality of spaced openings 6, the same can be adjusted for various sizes of springs.

Certain springs employed for operating motors have their outer ends centrally notched, as at 7 and the said ends, at the op-

posite sides of the notch are bent upon themselves to form hooks 8. These hooks 8 are engaged by anchor members 9 in the spring barrel 10. In this instance, my clamping strap 5 is arranged around the spring and the reduced end thereof is passed through the opening 7 so that my permanent retaining clamp will not interfere with the ready insertion of the spring in the barrel. In this 10 construction it is merely necessary to invert the barrel, that is, to arrange the open face thereof downwardly, and to tap lightly upon the closed gear carrying face thereof to jar the spring out of the barrel. Thus with my 15 improvement, it will be seen that springs may be arranged in the barrels or removed therefrom without the employment of tools. By constructing the clamps so that the same may be adjusted, the manufacturer will wind 20 the springs to the right size individually for the various makes and sizes of spring barrels, so that they will freely slip in the barrel with the clamps thereon.

In some instances, I have found it desirable to modify the shape of the opening 2 in the finger at the end of the spring. In Figure 6, the spring 1' is provided with a longer opening 2' than is usual, whereby the clamp may be more easily attached to the 30 spring.

Having described the invention, I claim:—

1. Means for holding a motor spring in a partly wound condition, comprising a comparatively thin metal strap which is passed

through the eye end of the partly wound ³⁵ spring, and means on said strap for adjustably connecting the ends thereof.

2. A means for holding a motor spring in partly wound condition, and wherein said spring has its outer convolution offset and ⁴⁰ slotted at the end thereof to provide an eye, comprising a comparatively thin metal band, gradually tapered from one to its opposite end having its widened end provided with spaced openings, said strap designed to be ⁴⁵ inserted through the eye of the spring, and to be arranged around the partly wound spring and having its reduced end passed through one of the openings in the second end of the strap and bent against said second ⁵⁰ end.

3. In a device for the purpose set forth, and in combination with a spring barrel, having an inwardly extending stud and a ⁵⁵ partly wound motor spring whose outer end is offset and slotted longitudinally and the said slot extending into the spring proper, said offset end providing a tongue, a strap having one of its ends provided with spaced ⁶⁰ openings, said strap being passed through the slot in the tongue and arranged around the spring and one end thereof being passed through one of the slots in the second end of the band and bent to hook shape whereby the strap is permanently sustained on the ⁶⁵ spring.

In testimony whereof I affix my signature.

RICHARD W. STEWART.
